UNITED STATES PATENT OFFICE

WALLACE D. WALKER, OF MEADVILLE, PENNSYLVANIA, ASSIGNOR TO HOOKLESS
FASTENER COMPANY, OF MEADVILLE, PENNSYLVANIA, A CORPORATION OF PENN-
SYLVANIA

COMBINED STOCKING PROTECTOR AND OVERSHOE

Application filed January 11, 1926. Serial No. 80,422.

This invention relates to waterproof foot-wear and has for its object to improve upon the heavy and bulky women's galoshes now in common use.

5 The only change made in these articles for many years has been in the replacement of buckles or clasps by a slide actuated interlocking fastener within the past three years. Although these galoshes have gone into wide 10 use, they are still made of heavy rubberized black fabric with heavy sole and vamp, and wide heel, and in addition commonly have a heavy cuff at the top fastened by snap buttons. Because of the heaviness of the inelastic 15 cloth and stiffness of bottom, little or no effort at fit or style is attempted by the manufacturer, and the user commonly buys oversize in order to fit different shoes. Frequently also, the custom is to have a loose or boot-like top which still further increases the bulk 20 and weight and decreases the fit. None of these rubberized cloth galoshes are or can be made in colors to match shoes, hose, skirts, or colored raincoats, nor of the desired light 25 weight and smallness of bulk to meet the best style and utility requirements, and to pack in small space.

According to this invention, a combined 30 stocking protector and overshoe is provided consisting of light weight and elastic foot fitting and ankle encircling portions, with preferably open heel, and closed by a slide actuated interlocking fastener to fit the foot and ankle tightly. The most convenient and ornamental location for the fastener is in 35 front, but it could be at the side or at the rear. The employment of the slide actuated type of fastener is practically essential in 40 producing a successful light weight footwear for this field inasmuch as clasps or buttons are not only unsightly and inconvenient to operate, but will also gape and prevent the desired fit. Also, they do not evenly distribute the strain as is required in order to prevent the light weight, rubber coated fabric

used from tearing. An article embodying this invention can be made in various colors, and while largely replacing galoshes is of such small bulk as to roll and be easily carried in a small package.

50 In the accompanying drawings:

Fig. 1 is a perspective of one embodiment of this invention.

Fig. 2 shows how the overshoe fits up under 55 the instep.

Fig. 3 is a section on the line 3a—3a of Fig. 1.

Referring to the drawings, this stocking protector and overshoe comprises a vamp or foot-fitting portion 10, having a light flexible sole 8 and elastic strap 9 fitting over the heel of the shoe for retaining the overshoe in place. The heel is preferably cut out as shown, similarly to a sandal. The top part of the overshoe and stocking protector comprises a light 60 weight elastic ankle encircling portion 11 which is slit longitudinally to facilitate taking off and putting on. The ankle encircling portion 11 is composed in the major part thereof of elastic material extending all the 65 way around the ankle and comprises a layer of light weight elastic fabric vulcanized to an outer sheet of light weight waterproof elastic material preferably rubber and is suitably colored. This fabric and rubber are 70 constructed to be elastic in one direction, that is, transversely, but relatively inelastic in the other or longitudinal direction. The fabric and rubber are both integral with the vamp or foot-fitting portion 10, the latter having 75 the rubber much thicker to withstand rough 80 usage and wear.

In order for the ankle encircling portion to be glove-fitting, it should stretch in all 85 parts and not more in some parts than in others. A substantially continuous fastener is therefore used to progressively open and close the longitudinal slit. In the form illustrated, this fastener is located at the front, although it will be understood that this fas- 90

tener may be located at the side or rear and yet function to enable the foot to be inserted and withdrawn without unduly stretching the ankle encircling portion. Another requisite for the close fitting ankle encircling portion 11 is that it must be flexible to conform to the curvature of the foot. One form of appropriate fastener, for example, is disclosed in Patent #1,243,458 dated October 10, 1917, wherein a plurality of locking members 12 are arranged in closely spaced relation along opposite edges of fabric stringers and operated by a slider. These stringers are secured to the sides of the slit and a slider 13 controls the engagement and disengagement of said fastener members. 19 is a metal bottom member to stop the slider and prevent tearing. 20 is a reinforcement extending longitudinally beyond the slit and slightly 20 under the sole to distribute the closing strain so as not to cause tearing across the foot fitting portion below the fastener. Specifically as shown the reinforcement 20 for the front opening protector extends on to the 25 foot fitting portion. For ornament as well as strength, this reinforcement can be extended up each side as shown in Figs. 1 and 3. The fabric stringers 15 are preferably vulcanized between rubber sheets 20, 20, as in 30 Fig. 3. Tongue 16 prevents the metal parts of the fastener from contacting with the hose, as in Fig. 3. The fastener slit preferably extends down the ankle encircling portion 11 and a short distance into the foot fitting portion 10, whereby removal and putting on of the overshoe is made easy. The foot fitting and ankle encircling portions 10 and 11 of this overshoe and the strap 9 may be variously colored, or to match whatever color 35 40 hose is used, or to match the wearer's shoes, skirt or coat, or the strap 9 in foot fitting portion 10 may be made of one color to agree with the shoes while the ankle encircling portion 11 may be made of another color. As 45 shown in Fig. 2, the sole is carried back and upward as at 18, with elastic edge 21 to closely fit the shoe arch, and far enough to reduce any tendency for water to leak inside.

Among the advantages of this invention 50 may be mentioned its neatness, lightness, and capacity of being rolled up in a small package to fit in a traveling bag or elsewhere without occupying the same space as rubbers or galoshes. Being light in weight and 55 glove-fitting, the overshoe is comfortable, warm, and effective as a stocking protector. Having the ankle encircling portion 11 made of material which is relatively inelastic longitudinally, prevents the portion of the overshoe 18 under the instep from pulling down upon the ankle encircling portion 11, and therefore helps keep the part 18 closely fitting up under the instep and off the ground. 60 However, the ankle encircling portion 11 is made elastic in transverse direction, that is,

around the ankle and lower leg so that a trim and stylish appearance is presented showing the contour of the shoe and ankle and not presenting the bulky, cumbersome appearance that is the case with the ordinary galosh. 70 The use of a fastener which exerts substantially continuous tension enables lighter material to be used by distributing the strains more uniformly than could buttons or clasps. This overshoe is comfortable for walking, it 75 being better adapted to conform to the motion of the foot and ankle than an ordinary galosh. This invention is especially adapted to low shoes or slippers, although it is equally capable of use with high shoes. 80

I am aware that various stretchable and nonstretchable fabrics have been used in footwear, and that the use of slide actuated interlocking fasteners in footwear is not broadly new, but I am not aware that such features have heretofore been combined in the novel manner here disclosed to produce an overshoe especially for women's wear meeting the demands of fit, style, color, lightness, etc. herein before stated. 85

I claim:

1. A combined stocking protector and overshoe comprising a foot fitting portion, an attached ankle encircling portion, the major part of which is of light weight elastic material and having a longitudinal slit, a plurality of closely spaced fastener elements along each side of said slit, the fastener elements on one side interlocking with the elements on the other whereby, when closed, the edges 100 of the slit are adjacent and the ankle encircling portion is stretched to effect the desired fit, and a reinforcement extending from the end of the slit on to the foot fitting portion to distribute the closing strain and to prevent tearing. 105

2. A combined stocking protector and overshoe comprising a foot fitting portion of rubber coated fabric, a strap embodied therein to engage the heel and hold the foot fitting portion in position, an attached light weight suitably colored ankle encircling portion of coated fabric, the major part of which is of elastic material adapted to stretch more transversely than longitudinally and having 115 a slit, a plurality of closely spaced fastener elements along each side of said slit, the fastener elements on one side interlocking with the elements on the other whereby, when closed, the edges of the slit are adjacent and the ankle encircling portion is stretched to effect the desired fit. 120

3. A combined stocking protector and overshoe comprising a foot fitting portion, an attached ankle encircling portion, the major part of which is of light weight elastic material and having a longitudinal slit, a plurality of closely spaced fastener elements along each side of said slit, the fastener elements on one side interlocking with the elements on 125 130

the other whereby, when closed, the edges of the slit are adjacent and the ankle encircling portion is stretched to effect the desired fit, and a strap embodied in the foot fitting portion to engage the heel and hold the foot fitting portion in position.

4. A combined stocking protector and overshoe comprising a foot fitting portion, an attached ankle encircling portion, the major part of which is of light weight elastic material and having a longitudinal slit, a plurality of closely spaced fastener elements along each side of said slit, the fastener elements on one side interlocking with the elements on the other whereby, when closed, the edges of the slit are adjacent and the ankle encircling portion is stretched to effect the desired fit, a reinforcement extending from the end of the slit on to the foot fitting portion to distribute the closing strain and to prevent tearing, and a strap embodied in the foot fitting portion to engage the heel and hold the foot fitting portion in position.

5. A combined stocking protector and overshoe comprising a foot fitting portion, an attached ankle encircling portion, the major part of which is of light weight elastic material and having a longitudinal slit, a plurality of closely spaced fastener elements along each side of said slit, the fastener elements on one side alternating and interlocking with the elements on the other side, a sliding device for progressively locking and unlocking said members, whereby when closed the edges of the slit are adjacent and the material is stretched around the ankle encircling portion to effect the desired fit, and a reinforcement extending from the end of the slit on to the foot fitting portion to distribute the closing strain and prevent tearing.

6. A combined stocking protector and overshoe comprising a foot fitting portion, an attached ankle encircling portion, the major part of which is of light weight elastic material adapted to stretch more transversely than longitudinally and having a slit extending partly into the front of the foot fitting portion, a plurality of closely spaced fastener elements along each side of said slit, the fastener elements on one side interlocking with the elements on the other whereby, when closed, the edges of the slit are adjacent and the ankle encircling portion is stretched to effect the desired fit, and a reinforcement extending from the end of the slit on to the foot fitting portion to distribute the closing strain and prevent tearing.

7. A combined stocking protector and overshoe comprising a foot fitting portion, an attached ankle encircling portion, the major part of which is of light weight elastic material and having a slit extending partly into the front of the foot fitting portion, a plurality of closely spaced fastener elements

along each side of said slit, the fastener elements on one side interlocking with the elements on the other whereby, when closed, the edges of the slit are adjacent and the ankle encircling portion is stretched to effect the desired fit, and a reinforcement extending from the end of the slit on to the foot fitting portion to distribute the closing strain, said reinforcement extending upwardly along each side of the slit.

8. A combined stocking protector and overshoe comprising a foot fitting portion with an open heel, a strap embodied therein to engage the heel of the shoe and hold the foot fitting portion in position, an attached ankle encircling portion, the major part of which is of light weight elastic material capable of being colored to match the wearer's apparel and adapted to stretch more transversely than longitudinally, said ankle encircling portion having a longitudinal slit, a plurality of closely spaced fastener elements along each side of said slit, the fastener elements on one side interlocking with the elements on the other whereby, when closed, the edges of the slit are adjacent and the ankle encircling portion is stretched to effect the desired fit, said slit extending partly into the foot fitting portion, and a reinforcement extending from the end of the slit on to the foot fitting portion to distribute the closing strain and prevent tearing and extending upwardly on each side of the slit.

9. A combined stocking protector and overshoe comprising a foot fitting portion, an attached ankle encircling portion, the major part of which is of light weight elastic material and having a longitudinal slit, a plurality of closely spaced fastener elements along each side of said slit, the fastener elements on one side interlocking with the elements on the other whereby, when closed, the edges of the slit are adjacent and the ankle encircling portion is stretched to effect the desired fit, a strap embodied in the foot fitting portion to engage the heel and hold the foot fitting portion in position, the sole of the foot fitting portion extending upwardly and rearwardly beneath the arch of the foot and provided with an elastic edge and held tightly against the arch by the pull of the strap and the fastening means.

10. A combined stocking protector and overshoe comprising a foot fitting portion, an attached ankle encircling portion, the major part of which is of light weight elastic material and having a longitudinal slit, a plurality of closely spaced fastener elements along each side of said slit, the fastener elements on one side interlocking with the elements on the other whereby, when closed, the edges of the slit are adjacent and the ankle encircling portion is stretched to effect the desired fit, a strap embodied in the foot fitting portion to engage the heel and hold the foot fit-

ting portion in position, a reinforcement extending from the end of the slit on to the foot fitting portion to distribute the closing strain and prevent tearing, the sole of the foot fitting portion extending upwardly and rearwardly beneath the arch of the foot and provided with an elastic edge and held tightly against the arch by the pull of the strap and the fastening means.

10 Signed at New York in the county of New York and State of New York this 8th day of January A. D. 1926.
